UNITED STATES PATENT OFFICE.

CHARLES OSBORNE, OF NEW YORK, N. Y., ASSIGNOR TO WHITING MANUFACTURING COMPANY, OF NEW YORK, N. Y., A CORPORATION OF NEW YORK.

DESIGN FOR A HANDLE FOR SPOONS, FORKS, OR SIMILAR ARTICLES.

43,156.

Specification for Design.

Patented Oct. 15, 1912.

Application filed February 19, 1912. Serial No. 678,726. Term of patent 14 years.

To all whom it may concern:

Be it known that I, CHARLES OSBORNE, a citizen of the United States, residing in the city of New York, borough of Manhattan, in the county and State of New York, have invented a new, original, and ornamental Design for a Handle for a Spoon, Fork, or Similar Article, of which the accompanying drawing is a representation.

Figure 1 is a view of the obverse face of

a spoon showing my new design, with a fork also shown in dotted lines, and Fig. 2 is a corresponding view of the reverse face.

I claim:

The ornamental design for a handle for a spoon, fork or similar article, as shown.

CHARLES OSBORNE.
